Inventor

O. A. Rystrom,

By Clarence O'Brien
Attorney

UNITED STATES PATENT OFFICE

OSCAR ALBIN RYSTROM, OF YORK, NEBRASKA

ROAD SIGN

Application filed July 21, 1927. Serial No. 207,439.

This invention relates to new and useful improvements in road signs and aims to provide a sign board mounted for revolution upon a post and that is of such a construction throughout its length that the sign will rotate at relatively slow speed regardless of the velocity of the wind, with the result that the advertising matter on both sides of the sign proper may be easily read by passing motorists.

The invention further aims to provide a rotating sign that will by reason of its continuous rotation attract the attention to a much greater degree than the stationary road signs now almost universally in use.

With the foregoing and other objects in view as the nature of the invention will be understood, the same comprises the novel form, combination and arrangement of parts hereinafter more fully described, shown in the accompanying drawings and claimed.

In the accompanying drawings forming part of this application and in which like reference characters designate corresponding parts:

Figure 1 is a view mainly in side elevation and partially in cross section of my improved sign.

Figure 2 is a top plan view thereof.

Figure 3 is an enlarged fragmentary section through the upper frame bar of the sign member per se and the upper end of the supporting post for more clearly disclosing the bearing connection therebetween, and

Figure 4 is a perspective of one of the end cleats used in the assembly of the sign unit per se.

Now having particular reference to the drawing, my novel sign embodies the provision of a vertical post 5 of any predetermined length and diameter suitably anchored at its lower end within the earth as suggested by the dotted lines in Figure 1. The sign unit, per se, consists of a pair of bars 6-6 adapted for arrangement in horizontally disposed parallel spaced relation and are each formed at their central portions with a relatively wide portion 7. This widened portion terminates at one end of the enlarged portion at 7' and at the opposite end thereof at 8'.

From these points, the opposite edge portions of the respective portions of the bars at opposite sides of the central portions thereof are curved longitudinally. These curved portions are denoted by the numeral 11, the curvature of one of these portions being at one edge thereof, while the other portion is curved at its opposite edge portion, in the manner clearly shown in Figure 2. The innermost portion 11' of the inner curved edges

55 of the respective curved portions of each bar are disposed on extensions of the longitudinal axis of the portion 7, the said innermost point of the curved portion being located at substantially one-fourth the distance inwardly 60 from the ends of each bar. Arranged at opposite sides of the bars 6-6 and spanning said bars are strips of sheet metal 8-8, shaped to conform to the curvature of the bars, the ends of which are extended beyond 65 the ends of the bars and are curved on a smaller arc than that of the edges of the bars as clearly disclosed in Figure 2. The ends of the strips of sheet metal at opposite sides of these bars 6-6 are suitably joined together, 70

75 while arranged over the ends of said bars 6-6 and within the sheet metal strips are metallic tips 9 which are shaped to conform to the curvature of the ends of the bars 6-6 and the ends of the metallic strips 8-8. The side 80 edges of these tips are flanged as at 10-10 which flanges engage over the edges of the bars 6-6 and between the metallic strips 8-8. Said tips may be secured to the bars and their flanges to the strips 8-8 in any 85 desirable manner. This formation of the sign board will provide relatively elongated air pockets 11-11 at the ends of the board and opposite sides thereof while opposed to the pockets throughout the greater length 90 thereof are vertical walls 10' to counteract to a high degree the velocity of the wind striking the pockets which will limit the rotation of the board regardless of the wind velocity.

95 The lowermost bar 6 is formed centrally with an opening 12 of a diameter greater than that of the post 5 and through which said post extends. The bottom surface of the uppermost bar 6 is formed with a circular socket 13 directly in alignment with the opening 12 in 100

the lowermost bar and within which is a suitable ball bearing structure 14. Arranged within the upper end of the post 5 is a block 15 formed centrally with a vertically extending pin 16 engageable in the bearing 14 as clearly disclosed in Figure 3. The sign is therefore rested in anti-frictional engagement upon the upper end of the post so that it may be easily turned by the wind. However, I do not desire to be understood as relying upon any particular character of bearing connection between the sign unit and the post as this is not to any extent whatever the essence of the invention.

Having thus described the invention, what I claim as new and desire to secure by Letters Patent is:—

1. In a revolving sign of the character described, an elongated and narrow board member, the center of said member being of enlarged thickness, the portions of the member extending outwardly from the enlarged portion being of curvilinear formation, the curved portions being curved in inverse directions from the enlarged portion, the innermost point of each curved portion being located at a point substantially one-fourth of the distance inwardly from the outer end of the member, and on an extension of the longitudinal axis of the enlarged portion, and a support, upon which the board member is adapted to be pivotally mounted at its enlarged portion.
2. In a revolving sign of the character described, an elongated and narrow board member, the center of said member being of enlarged thickness, the portions of the member extending outwardly from the enlarged portion being of curvilinear formation, the curved portions comprising oppositely disposed circular arcs, the innermost point of each curved portion being located at a point substantially one-fourth of the distance inwardly from the outer end of the member, said innermost point of the respective curved portions being disposed substantially on extensions of the longitudinal axis of the thickened portion of the board member, a tip member at each end of the board member, said tips being each of arcuate shape and in curvilinear relation with the adjacent curved portions of the board member, the arcuate curved construction being of relatively less diametrical curvature than the adjacent curved portions of the board member, and a support upon which the board member is adapted to be pivotally mounted at its enlarged central portion.

In testimony whereof I affix my signature.

OSCAR ALBIN RYSTROM.
